(57) **CLAIM**

The ornamental design for a mouth bit to prevent horses from chewing or biting, as shown and described.

DESCRIPTION

FIG. 1 is a perspective view of the mouth bit to prevent horses from chewing and biting showing my new design;

FIG. 2 is a side view of the invention thereof;

FIG. 3 is a left end view thereof;

FIG. 4 is a cross-sectional view thereof, taken along line "FIG. 4" in FIG. 2;

FIG. 5 is a cross-sectional view thereof, taken along line "FIG. 5" in FIG. 2;

FIG. 6 is a side view rotated 90 degrees from FIG. 2 thereof;

FIG. 7 is a right end view thereof;

FIG. 8 is a side view rotated 180 degrees from FIG. 2 thereof; and,

FIG. 9 is a side view rotated 270 degrees from FIG. 2 thereof.

The broken line showing of the horse and strap in FIG. 1 is for illustrative purposes only and forms no part of the claimed design.
